A. G. OSTER

CLOTHESLINE HOLDER

Filed March 8, 1922

Inventor:
Albert G. Oster.
By H. G. Fletcher,
atty.

Patented Dec. 9, 1924.

UNITED STATES PATENT OFFICE.

ALBERT G. OSTER, OF ST. LOUIS, MISSOURI, ASSIGNOR OF ONE-HALF TO MAYME A. OSTER, OF ST. LOUIS, MISSOURI.

CLOTHESLINE HOLDER.

Application filed March 8, 1922. Serial No. 542,016

To all whom it may concern:

Be it known that I, ALBERT G. OSTER, a citizen of the United States of America, and a resident of the city of St. Louis and State 5 of Missouri, have invented certain new and useful Improvements in a Clothesline Holder, of which the following is a specification.

The primary object of this invention is to provide an improved automatic clamping 10 device, to be secured to clothes line posts and the like, so that a clothes line can be quickly and demountably secured thereto.

Another object of the invention is to provide a clothes line holder with an automatic 15 clamping means which will readily hold the line tightly therein against slipping, and at the same time allow for the clothes line to be readily removed therefrom.

Other and further objects will appear in 20 the specification and be specifically pointed out in the appended claims, reference being had to the accompanying drawings exemplifying the invention, and in which:—

Figure 1 is a perspective view of a portion 25 of a clothes line post showing this improved attachment secured thereto, and supporting a clothes line.

Figure 2 is an enlarged side elevation of 30 this improved device.

Figure 3 is an enlarged plan view of Fig. 2.

Figure 4 is an enlarged transverse section taken on the line IV—IV of Fig. 1.

With reference to the accompanying drawings this improved attachment is comprised 35 of an angular metallic bracket 1 having a vertically disposed portion 2 in which is formed a pair of openings 3 for the reception of the fastening screws 4 for securing 40 it to a post 5 or the like.

The bracket 1 is also provided with a horizontal portion 6, and formed on said portion 6 and in opposite disposition from the vertically extending portion 2 is another 45 extending portion 7 which is provided with a pair of openings 8, each opening being for the reception of a respective end 9 of a looped wire 10.

The looped wire 10 is resilient and con- 50 structed of relatively heavy material and is peculiarly shaped, the intermediate portion of said wire being upwardly bent and forming a lip 11, the depending side portions 12 of a lip 11, each terminating into a horizontally 55 said lip 11, each terminating into a horizontally extending portion 6 of the bracket 1.

Each of the portions 13 terminates downwardly as designated at 14 and is formed into a loop 15, the upwardly extending portion 16 of each loop merging into each respective end 9 of the looped wire 10. 60

The disposition of the lip 11 is above the horizontal portion 6 of the bracket 1, and from the disclosure of Fig. 2, is extended at some distance from the place or point at which the ends 9 of the looped wire 10 are 65 rigidly secured to the upwardly extending portion 7 of the bracket 1. In this connection, when the lip portion 11 is elevated, hinging or fulcrum portions thereof and to the horizontal portions 13 will be created in 70 the loops 15.

In the securing of a clothes line to a series of attachments of this improved character, when a number of them are secured 75 to posts and the like, a portion of the clothes line 17 is placed on the horizontal portion 6 of the bracket 1 between the vertical portion 2 thereof and the lip portion 11 of the wire loop 10, and the clothes line is then engaged on each side of the bracket portion 6 by the manipulator and pulled against the lip portion 11 where it will be engaged beneath the rounded portions 18 of said lip portion, beneath the horizontal portions 13 and between said horizontal portions and the 80 bracket portion 6, as shown in Figs. 1, 3 and 4.

On account of the spring compression of the loops 15, a clamping strain will be given 85 downwardly to the horizontal portions 13 90 wherein the clothes line 17 will be pinched or clamped between said horizontal portions 13 and the corners 19 of the bracket portion 6, the clamping strain of said portion 13 95 against the clothes line being so great as to prevent the clothes line from being slid from beneath the clamping portions 13 when strain is applied thereto in the directions of the double-arrow 20 shown in Fig. 1, said direction of pulling being angular to the direction in which the clothes line portion was 100 engaged beneath the lip 11.

In detaching a clothes line from a plurality of these improved attachments, the engaging portion of the clothes line is pushed 105 outwardly from beneath the portions 13 towards the vertically extending portion 2 of the bracket 1.

What I claim is:—

1. A line fastener having an extending 110

portion and a pair of spaced apart resilient portions leading from said extending portion arranged parallel and in straddling relation thereto, each of said resilient portions adapted to co-operate with a respective side edge of said extending portion.

2. A clothes line holder comprising a supporting base having means for securing it to a post or the like, and a pair of resilient clamping parts rigidly secured at one end to said base each having a portion arranged parallel thereto and spaced a distance apart wider than said base.

3. A holder for a clothes line comprising a supporting base provided with means for securing it to a post or the like, and a wire loop secured to said base formed so as to provide a pair of clamping portions which parallel said base adjacent the side edges thereof, said clamping portions being spaced apart a distance wider than said base.

4. A holder for a clothes line comprising a supporting bracket having an extending portion, a wire loop having its ends secured to said extending portion, said loop being provided with a pair of portions which approximately parallel said extending portion on a plane thereabove, said pair of portions being spaced apart a distance wider than said extending portion.

5. A holder for a clothes line comprising a supporting bracket having an extending portion, a wire loop having its ends secured to said bracket, said loop being provided with a pair of portions which approximately parallel the extending portion of said bracket, and an up turned portion forming a receiving lip to said paralleling portions of said loop.

6. A holder for a clothes line comprising a bracket having a base portion, said base portion having a portion extending upwardly therefrom, a wire loop secured at its ends to said upwardly extending portion, said wire loop having a pair of spaced apart portions extending parallel to said base portion each being adjacent a side edge of said base portion, and an up turned lip adjoining said paralleling portions.

7. A line fastener having an extending portion and a pair of spaced apart resilient portions leading from said extending portion arranged parallel and in straddling relation over said extending portion, said spaced apart portions being joined at their extending ends, each of said resilient portions being arranged so as to co-operate with a respective side edge of said extending portion for clamping a rope therebetween.

ALBERT G. OSTER.
